UNITED STATES PATENT OFFICE.

VINCENT O. RITCHAY AND HOWARD A. TRIMMER, OF CORAOPOLIS, PENNSYLVANIA.

BONE-BURNER.

1,160,657.

Specification of Letters Patent. Patented Nov. 16, 1915.

Application filed July 6, 1915. Serial No. 38,230.

To all whom it may concern:

Be it known that we, VINCENT O. RITCHAY, and HOWARD A. TRIMMER, citizens of the United States, residing at Coraopolis, in the 5 county of Allegheny and State of Pennsylvania, have invented certain new and useful Improvements in Bone-Burners, of which the following is a specification.

This invention relates to a bone burner 10 and has for its object to provide in a manner as hereinafter set forth a novel construction of burner, oven or retort for thoroughly and automatically subjecting bone to the action of a flame so as to disintegrate the bone 15 to such an extent that it can be employed for purposes of bone-black, and for other purposes wherein the disintegrated bone will be found applicable.

A further object of the invention is to provide 20 a bone burner having means, in a manner as hereinafter set forth to arrest the discharge of bone dust when forced through the outlet flue and to further deflect such arrested bone dust in a manner whereby it 25 will be directed back to the combustion chamber under circumstances reducing waste to a minimum.

A further object of the invention is to provide 30 a bone burner with means in a manner as hereinafter set forth, whereby the bone will be fed by gravity through the combustion chamber and to further provide the burner with means whereby gas, oil, or coal can be utilized for burning the bone 35 and the flame carried directly against the bone as it is fed by gravity through the combustion chamber under such conditions overcoming the necessity of handling the bone within the burner and by such an arrangement 40 enabling the entire structure to be operated by a single attendant who could regulate the supply of bone to the burner in accordance with the amount of disintegrated bone that has been discharged therefrom.

A further object of the invention is to provide 45 a bone burner with means, in a manner as hereinafter set forth, to constitute a cooler for the disintegrated bone after the latter has been discharged from the combustion chamber.

Further objects of the invention are to provide 50 a bone burner which is simple in its construction and arrangement, strong, durable, thoroughly efficient in its use, and comparatively inexpensive to set up.

With the foregoing and other objects in view the invention consists of the novel construction, combination and arrangement of parts as hereinafter more specifically described and illustrated in the accompanying drawings, wherein is found an embodiment of the invention, but it is to be understood that changes, variations and modifications can be resorted to which come within the scope of the claims hereunto appended.

In the drawings wherein like reference characters denote corresponding parts throughout the several views:—Figure 1 is a vertical sectional view of a bone burner 70 in accordance with this invention. Fig. 2 is a vertical section on line A—A, Fig. 1. Fig. 3 is a rear elevation. Fig. 4 is a sectional plan on line B—B, Fig. 1. Fig. 5 is a like view on line C—C, Fig. 1. Fig. 6 is a similar view on line D—D, Fig. 1. Fig. 7 is a sectional plan on line E—E, Fig. 1. Fig. 8 is a longitudinal sectional view, broken away, of a supply controlling device. Fig. 9 is a cross sectional view of Fig. 8.

Referring to the drawings in detail 1 denotes a base formed of a pair of front and rear uprights and each front upright is connected to a rear upright by an arch-shaped element 2. The uprights of the base, as well as the arch-shaped elements thereof, are constructed preferably of brick. Mounted in the base 1 at the top thereof are horizontally disposed T-bars which are employed for reinforcing and bracing purposes.

The base 1 supports a structure containing a combustion chamber and said structure includes a front wall 4, top wall 5, rear wall 6, and a bottom 7. The front wall 4 has an entrance opening 8 closed by a door 9. The front wall 4 below the door opening 8 has a pocket 10 in which can be arranged an oil burner or gas burner in a manner whereby the flame will be directed into the combustion chamber 11 which is formed by the 95 walls 4, 5, 6, bottom 7 and side walls 12, 13. Leading to the burner and mounted in the pocket 10 is an oil or gas supply pipe 14.

The burner structure is built of brick and is reinforced exteriorly, at the sides, front and rear by vertically disposed metallic strips 15. The strips 15 at the front and rear of the burner structure are connected together by tie bars 16 and the strips 15 as well as the sides of the burning structure are connected together by tie bars 17. Mounted in the lower portion of the struc-

ture are horizontally disposed inverted T-bars 18 providing a reinforcement. The rear wall 6 is triangular in contour, as well as the bottom 7, but the latter is positioned 5 in a reversed manner with respect to said rear wall 6. The said bottom 7 is of a height as to extend to approximately half the height of said rear wall 6 and near the inner end thereof, in proximity to the rear 10 wall 6, has a baffle 19.

The inclined inner face of the rear wall 6 has a lining of tile as indicated at 20 and which extends from the upper portion of said inclined inner face to the lower end 15 thereof. The inclined face of the bottom 7, as indicated at 21 opposes but is spaced from the lower portion of the tile lining 20, under such conditions providing a discharge runway which is divided by inclined partitions 23 into a series of discharge channels 24.

The side walls 12, 13, are of a thickness less than the thickness of the uprights of the base 1, but said side walls are flushed 25 with the outer face of said uprights and by setting up the side walls, with respect to the uprights, in a manner as stated, supporting ledges 25 are provided upon which is mounted a rectangular frame 26, constituting 30 a directing element and into which the lower ends of the discharge channels 24 open. The inner faces of the ends of the frame 26 are beveled as at 27.

The front uprights of each pair of uprights have lateral extending supporting members 28 which are anchored therein and extend therefrom and mounted upon said members 28 in the directing element is a cooler comprising a casing consisting of a 35 body portion 29, having a funnel-shaped bottom 30 which communicates with a discharge pipe 31, provided with a cut-off 32. Arranged within the body portion 29 are cooling pipes 33, to which a cooling medium 40 is supplied and discharged in any suitable manner and the said cooler element is adapted to receive the disintegrated bone from the combustion chamber 11, through the medium of the discharge channels 24 and directing element and when the disintegrated bone is supplied to the cooling element it 45 is cooled, and when desired discharge from the cooling element can be had through the pipe 31.

50 The baffle 19, upon the bottom 7, is in the form of a checker work, as clearly illustrated in Fig. 2, and arranged in advance of the said baffle 19 is the inner end of an air supply pipe 34. The latter is built in the 55 bottom 7 and the inlet end of the said supply pipe is positioned just in advance of a burner which is arranged within the pocket 10 whereby the necessary amount of air can be supplied to create the proper combustion. 60

The top 5 of the burner structure has its lower face set up in the form of an arch as indicated at 35 and the said top 5 in proximity to its rear end is formed with a transversely extending inlet opening 36 70 through which the bone to be disintegrated is supplied by gravity to the combustion chamber 11, and upon the inclined face of the rear wall 6 whereby as the bone shifts down said inclined surface it will be attacked by the flame from the burner and 75 disintegrated.

Arranged upon the burner structure is a combined flue, hopper and heating chamber structure which is built of brick, and 80 is provided in the lower portion at the rear thereof with a heating chamber 37 of triangular contour and which communicates with the inlet 36. The bottom of the chamber 37 is inclined as at 38 and has a face of 85 tile 39. Secured to the tiles 39 are vertically disposed spaced triangular bars 40 which divide the chamber 37 into a series of channels 41. The partitions 40 as well as the inclined surface of the bottom are of 90 less height than the height of the chamber 37 and extending across the top of the partitions 40 is a horizontally disposed apertured member 42.

Arranged forward of the chamber 37 is a 95 dust flue 43, which has its top provided with a baffle 44 and which has its top opening into the chamber 37 forward with respect to the member 42. The dust flue 43 is near the same height as the chamber 37 and the 100 lower portion of said flue 43 opens into a pair of forward projecting and inward inclined flues 44, 45, which open into the lower end of a vertically disposed dust flue 46 of materially less width and breadth than 105 the width and breadth of the flue 43. Opening into the lower end of the flue 46, as well as into the bottom of the flue 43, is a horizontally disposed flue 47 which is disposed centrally with respect to the flue 43. The 110 flue 43 is of greater height than the flue 43. The lower end of the flue 46 has an entrance opening 48, normally closed by a door 49 and each of the flues 44, 46, has an entrance opening 50 normally closed by a 115 door 51. The openings 48 and 50 and doors 49 and 51, provide means whereby access can be had to the flues 44, 45 and 46 for the purpose of cleaning them and the openings 48 and door 49 also permit access being had 120 to the flue 47. Arranged within the combined flue, hopper and heating chamber structure, at the upper portion thereof and above the chamber 37, and flues 43, 44 and 45, is a hopper chamber 52, having its bottom provided with a face of tiling 53. The bottom 54 of the hopper chamber inclines from the front and rear toward the center and is formed with an outlet 55. 125

Seated in the outlet 55 of the hopper 130

chamber 52 is a material supply controlling element 60' formed of an inner and an outer elongated cylindrical member 56, 57 respectively. The outer member 56 is formed with 5 pairs of slots 58 and the slots of each pair of rows are arranged opposite each other. The inner member 57 is formed throughout with rows of slots 59 arranged diametrically opposite each other. The slots 58, 59 10 are rectangular in contour and the slots 58 are adapted to register with the slots 59 whereby the material can be supplied from the hopper, through the apertured member 42, into the heating chamber 37. The openings 15 in the member 52 register with the channels 41.

One end of each of the members 56, 57, is closed as indicated at 60, 61, and extending through the openings 62 formed in the 20 end 60 is a turning bar 63, which is fixedly secured in the boss 64 integral with the end 61 and the member 57. The bar 63 is journaled in one side of the combined flue, hopper and heating chamber structure and projects outwardly from said side and is provided with a hand wheel 65.

The controlling element is of a length substantially equal to the width of the combined flue, hopper and heating chamber 30 structure and the outer member 56 of said element is fixedly secured within said structure so that it cannot be shifted. The inner member 57 turns within the outer member 56, through the medium of a bar 63 and a 35 hand wheel 65. The controlling element provides for regulating the supply from the hopper to the heating chamber 37 and owing to the fact that the inner member 57 can be revolved the clogging of the slots 58 and 59 40 by the material to be treated can be overcome.

The rear of the combined flue, hopper and heating chamber structure has an opening 66, closed by a door 67 and by such an arrangement access can be had to the heating chamber 37.

The combined flue, hopper and heating chamber structure has the top thereof formed with a vertically disposed dust flue 50 68 which has its lower end opening into the forward portion of the hopper chamber 52, and furthermore communicates with the upper portion of the dust flue 46 by an inclined flue 69, the top wall 70 of which extends across the upper end of the flue 46.

The top of the flue 70 constitutes a baffle deflecting the dust into the hopper chamber 52 and in such connection it will be stated that when the draft becomes very great in 60 the retort chamber 11, the bone dust or certain portion thereof, is carried up through the heating chamber 37, into the flue 48, thence through the flues 44, 45, and 47, into the flue 46, where the dust is carried upward 65 and strikes against the baffle 70 and is then

deflected into the hopper chamber 53, by this arrangement waste is reduced to a minimum.

The inclined bottom wall of the chamber 37 constitutes what may be termed a feeding surface for the material to the retort chamber 11 and the partitions 39 cause the feed to be uniform and prevent clogging thereof at the inlet 36. When the material is fed to the retort chamber it is attacked 75 by the flame and the bone is disintegrated.

Heat from the combustion chamber, and in some instances the flame due to the fact that the gas or oil is fed into the burner, is passed up into the chamber 37 and heats 80 the material as it is being fed to the retort chamber. The baffle 19, which is formed of checker work, will also assist in spreading the flame so that the material will be fairly attacked within the combustion chamber. 85

From the foregoing it is obvious that we have described a structure whereby during the movement of material from the heating chamber to the combustion chamber it will be continuously subjected to the action of 90 heat disintegrating the material and after the same has been disintegrated it can be cooled due to the fact that the material is discharged from the combustion chamber into the cooler. 95

What we claim is:—

1. A bone burner comprising a combustion chamber, a burner element associated therewith, a heating chamber arranged above and communicating with the combustion chamber and provided with an inclined bottom having mounted thereon vertical partitions forming a plurality of feed channels leading to the point of communication between said chambers, means for supplying material to said channels and an outlet flue leading from said heating chamber. 105

2. A bone burner comprising a combustion chamber, a burner element associated therewith, a heating chamber arranged above and communicating with the combustion chamber provided with an inclined bottom having mounted thereon vertical partitions forming a plurality of feed channels leading to the point of communication between said chambers, a hopper chamber arranged above and communicating with said heating chamber, means for controlling the supply of material from the hopper chamber to said heating chamber, a flue structure 110 leading from said heating chamber and opening into said hopper chamber, and a baffle arranged in said flue structure near said hopper chamber. 115

3. A bone burner comprising a combustion chamber, a burner element associated therewith, a heating chamber arranged above said and opening into said combustion chamber, means whereby material to be treated is fed by gravity through said chamber. 125 130

ber, means to provide a channeled outlet for said retort chamber, and a cooler receiving the treated material from said channeled outlet.

5. A bone burner comprising a combustion chamber, a heating chamber opening thereinto, a hopper chamber communicating with the heating chamber, means to provide an outlet flue leading from said heating chamber and communicating with said hopper chamber, and a baffle arranged in said flue for deflecting bone dust into said hopper chamber.

15. A bone burner comprising a combustion chamber, a heating chamber opening thereinto, a hopper chamber communicating with the heating chamber, means to provide an outlet flue leading from said heating chamber, and communicating with said hopper chamber, a baffle arranged in said flue for deflecting bone dust into said hopper chamber, and means for controlling the supply from said hopper chamber to said heating chamber.

25. A bone burner comprising a combustion chamber, a heating chamber opening thereinto, a hopper chamber communicating with the heating chamber, means to provide an outlet flue leading from said heating chamber, and communicating with said hopper chamber, a baffle arranged in said flue for deflecting bone dust into said hopper chamber, said heating and combustion chambers having means to cause the feeding by gravity of material to be treated, and a cooler for receiving the treated material from said retort chamber.

40. A bone burner comprising a combustion chamber, a heating chamber opening thereinto, a hopper chamber communicating with the heating chamber, means to provide an outlet flue leading from said heating chamber, and communicating with said hopper chamber, a baffle arranged in said flue for deflecting bone dust into said hopper chamber, means for controlling the supply from said hopper chamber to said heating chamber, said heating and combustion chambers having means to cause the feeding of the material to be treated by gravity, and a cooler for receiving the treated material from said retort chambers.

45. A bone burner comprising a combustion chamber having the inner face of its rear wall inclined and its bottom provided with a baffle in proximity to said inclined face.

55. A bone burner comprising a combustion chamber having the inner face of its rear wall inclined and its bottom provided with a baffle in proximity to said inclined face, said baffle being in the form of a checker work.

65. A bone burner comprising a combustion chamber having the inner face of its

rear wall inclined and its bottom provided with a baffle in proximity to said inclined face, and means to provide a channeled outlet for said chamber.

75. 11. A bone burner comprising a combustion chamber having the inner face of its rear wall inclined and its bottom provided with a baffle in proximity to said inclined face, said baffle being in the form of a checker work, and means to provide a channeled outlet for said chamber.

80. 12. A bone burner comprising a combustion chamber having the inner face of its rear wall inclined and its bottom provided with a baffle, in proximity to said inclined face, means to provide a channeled outlet for said chamber, and a cooler for receiving treated material from said channeled outlet.

85. 13. A bone burner comprising a combustion chamber having the inner face of its rear wall inclined and its bottom provided with a baffle in proximity to said inclined face, said baffle being in the form of a checker work, means to provide a channeled outlet for said chamber, and a cooler for receiving treated material from said channeled outlet.

90. 14. A bone burner comprising a combustion chamber having the inner face of its rear wall inclined and its bottom provided with a baffle, in proximity to said inclined face, means to provide a channeled outlet for said chamber, a cooler for receiving treated material from said channeled outlet, and a director element interposed between the lower terminus of said channeled outlet and said cooler.

95. 15. A bone burner comprising a combustion chamber, a heating chamber opening thereinto, a hopper chamber communicating with the heating chamber, a stationary hollow cylindrical slotted member arranged at the point of communication between the hopper and heating chambers, and a shiftable hollow cylindrical member arranged within said stationary member.

100. 16. A bone burner comprising a combustion chamber, a heating chamber operating thereinto, a hopper chamber communicating with the heating chamber, and a pair of hollow cylindrical slotted members positioned at the point of communication between said hopper and heating chambers, one of said members being shiftable relative to the other.

105. 17. A bone burner comprising a combustion chamber, having inclined rear wall and bottom, said bottom having one face reversely inclined with respect to the rear wall and spaced therefrom, thereby providing an inclined outlet for said chamber, and means arranged within said outlet to provide a plurality of discharge channels.

110. 18. A bone burner comprising a combustion chamber having an inclined rear wall,

- a checker work baffle mounted upon the bottom of the chamber and spaced from said rear wall, and a burner element associated with said chamber.
- 5 19. A bone burner comprising a combustion chamber having an inclined rear wall, a checker work baffle mounted upon the bottom of the chamber and spaced from said rear wall, and a burner element associated with 10 said chamber, and means for conducting air through the bottom of said chamber and supplying it to the inner end of the burner.
- 10 20. A bone burner comprising a combustion chamber having an inclined rear wall, a checker work baffle mounted upon the bottom of the chamber and spaced from said rear wall, a burner element associated with 15 said chamber, means for conducting air through the bottom of said chamber and supplying it to the inner end of the burner, 20 said bottom and rear wall being arranged in such relation with respect to each other to provide an inclined outlet passage.
- 20 21. A bone burner comprising a combustion chamber having an inclined rear wall, a checker work baffle mounted upon the bottom of the chamber and spaced from said rear wall, a burner element associated with 25 said chamber, means for conducting air through the bottom of said chamber and supplying it to the inner end of the burner, 30 said bottom and rear wall being arranged in such relation with respect to each other as to provide an inclined outlet passage, and 35 a cooler arranged below said combustion chamber and into which said outlet opens.
22. A bone burner comprising a combustion chamber and a burner element associated therewith, a heating chamber communicating with said combustion chamber, 40 and provided with means for feeding material to said combustion chamber, a hopper chamber communicating with said heating chamber, means for controlling communication between the heating and hopper chambers, flues leading from the heating chamber, and means associated with the flues for deflecting bone dust passing through said hopper chamber.
- 45 23. A bone burner comprising a combustion chamber, a burner element associated therewith, a heating chamber communicating with said combustion chamber and provided with means for feeding material to 50 said combustion chamber, a hopper chamber communicating with said heating chamber, means for controlling communication between the heating and hopper chambers, flues leading from the heating chamber, and means associated with the flues for deflecting bone dust through said hopper chamber, 55 said combustion chamber having an outlet for treated material and a cooler for receiving the treated material from said outlet.
- 60 In testimony whereof we affix our signatures in presence of two witnesses.
